UNITED STATES PATENT OFFICE.

GEORGE PLUMMER FAY, OF ATHENS, PENNSYLVANIA.

ARTICLE-HOLDER.

No. 892,238.

Specification of Letters Patent.

Patented June 30, 1908.

Application filed March 4, 1908. Serial No. 419,172.

To all whom it may concern:

Be it known that I, GEORGE P. FAY, a citizen of the United States, residing at Athens, in the county of Bradford and State of Pennsylvania, have invented certain new and useful Improvements in Article - Holders, of which the following is a specification.

This invention relates to that class of article-holders known as wall-pockets, and has 10 for its object to provide a device of this kind which is simple in construction, and which will effectually serve the purpose for which it is designed.

A further object is to provide a wall-pocket 15 which may be folded into small compass for convenience in packing and shipping the same.

In the accompanying drawing, Figure 1 is a front elevation of the invention. Fig. 2 is 20 an edge view. Fig. 3 is a similar view showing the device folded. Fig. 4 is a front elevation of a modification.

As shown in Figs. 1, 2 and 3, the wall-pocket is in two sections which may be separated, 25 and folded or placed together as shown in Fig. 3. These two sections are indicated at 5 and 6, respectively, the former being the top and the latter the bottom section.

The top section comprises a back-board or 30 plate 7 to the face of which are secured boxes 8 having hinged lids 9. These boxes are spaced apart vertically sufficiently to enable the box-lids to be swung open. The boxes are secured in place on the back-board by 35 screws or other suitable fastening means 10 passing through the rear wall of the box and into the back-board.

The bottom section 6 comprises a back-board 11 to which are secured boxes 12 in the 40 same manner as the boxes 8. Catches 13 are provided for holding the lids of the boxes 8 and 12 closed.

In the bottom edge of the top section are screw-hooks 14, and in the top edge of the 45 bottom section are screw-eyes 15 which are engageable by the aforesaid screw - hooks whereby the two sections are connected as shown in Figs. 1 and 2. In the upper edge of the top section are screw-eyes 16 whereby 50 the device is hung on a nail secured to the wall or other support. The bottom box of

the top section projects below the lower edge of the back-board 7 sufficiently to cover the joint between the two sections thereby hiding the same so that the back-board will 55 appear as being in one piece and its appearance will not be marred.

Upon disengaging the hooks 14 from the eyes 15, the two sections 5 and 6 can be placed together face-to-face as shown in Fig. 60 3. The space between the boxes is unobstructed, and the relative position of the boxes is such that the boxes of one section will fit or enter between the boxes of the other section. This arrangement greatly reduces 65 the compass of the device when it is in folded position, and makes it easy to carry and pack, as well as less liable to damage.

The device herein described is simple in construction and therefore can be cheaply 70 produced. It affords convenient means for holding a large number of articles, and it effectually serves the purpose for which it is designed. Ornamentation as fancy dictates may be resorted to. 75

The modified form of wall-pocket illustrated in Fig. 4 is without the folding feature, it consisting in a single back-board 17 to which boxes 18 are secured in the same manner as hereinbefore described. The back-board also has screw-eyes 19 in its upper edge 80 for hanging it.

I claim:

1. An article-holder comprising a back-board consisting of separable sections, spaced 85 boxes secured to the face of each section, the relative position of the boxes being such that those of one section will enter between those of the other section when said sections are placed face-to-face. 90

2. An article-holder comprising a back-board consisting of separable sections, and a plurality of boxes secured to the face of each section, one of said boxes overlapping the joint between the back-board sections. 95

In testimony whereof I affix my signature, in presence of two witnesses.

GEORGE PLUMMER FAY.
